UNITED STATES PATENT OFFICE.

HARRY R. HOLDEMAN, OF LOS ANGELES, CALIFORNIA, ASSIGNOR TO THE J. M. FELDMAN CO. INC., OF LOS ANGELES, CALIFORNIA.

DESIGN FOR AN ITALIAN-EFFECT PLATE FOR LIGHTING FIXTURES OR SIMILAR ARTICLES.

Application filed March 13, 1928. Serial No. 25,825. Term of patent 3½ years.

To all whom it may concern:

Be it known that I, HARRY R. HOLDEMAN, a citizen of the United States, residing at Los Angeles, in the county of Los Angeles and State of California, have invented a new, original, and ornamental Design for an Italian Effect Plate for Lighting Fixtures or Similar Articles, of which the following is a specification, reference being had to the accompanying drawing, forming part thereof.

The figure is an elevational view of an Italian effect plate for lighting fixtures or similar articles, showing my new design.

I claim:

The ornamental design for an Italian effect plate for lighting fixtures or similar articles, as shown.

HARRY R. HOLDEMAN.
